UNITED STATES PATENT OFFICE.

JOSEPH VERTUNNI AND ABRAHAM T. ORELLI, OF LONG BEACH, CALIFORNIA.

SHEARING-MACHINE.

1,122,558.

Specification of Letters Patent.

Patented Dec. 29, 1914.

Application filed July 7, 1913. Serial No. 777,676.

To all whom it may concern:

Be it known that we, JOSEPH VERTUNNI and ABRAHAM T. ORELLI, citizens of the United States, residing at Long Beach, in the county of Los Angeles and State of California, have invented a new and useful Improvement in Shearing-Machines, of which the following is a specification.

This invention relates to shearing machines, and particularly machines adapted for cutting leather, and the principal object is to provide a leather cutting machine which may be used to cut straight or beveled edges.

It is a further object to provide a shearing machine having a blade slidably supported in relation to the frame, and provided with a leverage that will provide a parallel and shearing action of the blade in relation to the table.

In the drawings accompanying this specification—Figure 1 is a front elevation of the machine showing the slide extended and broken away showing a cross section of the same. Fig. 2 is a sectional elevation view from the front and carried through the supporting bracket and the cutting slot. Fig. 3 is a section on the line 3—3, a portion of the frame being shown in end elevation. Fig. 4 is a plan view of the bracket end of the frame.

More specifically in the drawings, 5 designates the base having the top plate 6 parallel with the front face of which is the slotted guideway provided to carry the flange guide plate 7 a slot 8 providing a cutting edge at its upper front corner for the knife blade, and an aperture 13 preferably extending longitudinally of the frame 40 through which the scraps of leather may fall to the recess provided under the top plate. Mounted on one end of the frame is the bracket 9 vertically disposed above the plate adjacent to the end and provided with an arm 10 which extends in a substantially horizontal direction over the top and parallel with the cutting edge slot, this arm is preferably slotted at its end and points intermediate forming slots 11 and 12, in the former of which is pivoted the operating lever 14 on the bolt 15, this operating arm is of the configuration shown and is of sufficient length to provide leverage action sufficient to cut the usual sole leather, for which this invention is particularly designed, is provided with a plurality of ears 16 and 17

which are slotted and edged to embrace connections intermediate of the lever and the knife blade.

The ear 17 is directly pivoted to and embraces a stud 18 mounted on the knife blade holder 19, this knife blade holder being provided with a rabbet which leaves an extended shoulder 20 against which the knife blade 21 is adapted to engage, the blade being held in position on the holder 19 by counter sunk screws 22. The holder 19 is of general elongated shape, the end adjacent to the bracket 9 being provided with a guiding ear 24, the opposite end being similarly provided with a guiding ear 25, these latter being offset from the line of the cutting edge slot and are adapted to slide in slots in the top plate adjacent to the ends of the knife edge slot, a suitable slot being formed in the bracket to accommodate the ear 24 and to provide a bearing to guide the holder vertically in relation to the cutting edge and the top plate. The ear 24 is also provided with a pivot pin 26 to which is pivotally connected a pair of connecting straps 27 which straddle the ear and the end of the upper arm 28 of the bell-crank lever, which is pivoted on the pivot pin 29 carried through the frame and the slot 12 therein. The lower arm 30 of the bell crank lever is pivotally connected to the yoke end of the strap 31 by the pivot pin 32, the other end of this connecting strap being pivoted in the slotted ear 16 by means of the bolt 33.

With the slide 7 in position shown in Fig. 1, the blade is elevated and ready to cut. In the view Fig. 2 shows the blade housed in the slot 8 having passed the cutting edge and reached the limit of its movement.

The slide 7 is provided with a tongue 40 which is adapted to slide in the guide way previously mentioned parallel with the cutting edge slot 8, the slide having a base flange 41 provided with a slot 42 which embraces the clamping screw 43 provided with a knurled head 44. Extending upwardly from the base flange is the vertical flange 45, the lower corner 46 of which is adapted to register or be parallel with the cutting edge of the slot 8, the face being inclined away from the knife as clearly shown in Fig. 3 so that the edges of the pieces of leather desired to be tapered or skewed are inserted under the knife blade in its raised position with the face to which the bevel is approached in contact with the inclined face

of the flange 45 when the shearing action of the knife blade will give the proper bevel. The flange base 41 may be adjustably secured so that the angle may be changed if 5 desired and as before stated, the slide can be drawn out of its engaging position with the knife by releasing the screw 43 and sliding the same outwardly as shown in Fig. 1. The arm 28 of the bell crank being longer 10 than the arm 30 the corner of the blade and knife holder nearest the finger 24 is depressed more rapidly than the portion of the blade outwardly disposed so that the blade cuts at an angle to the top blade.

15 What we claim is:

1. In a shearing machine, the combination 20 of a plate having a slot providing a cutting edge, a bracket on the plate, a rigid arm on the bracket extending parallel with the slot, an operating lever pivoted to the outer 25 end of the arm, a knife blade holder extending parallel with the slot in the frame pivotally connected adjacent to one end to the underside of the lever, a bell crank lever on 30 the arm having upwardly and downwardly projecting arms extending toward the operating lever, a link connecting the lower arm of the bell crank lever to the operating lever at a point intermediate of the pivotal 35 mounting of the arm and its connection with the blade holder, and a link connecting the other arm of the bell crank lever to the blade holder adjacent to the end thereof and opposite its connection with the operating lever.

2. In a shearing machine, the combination 40 of a plate having a slot providing a cutting edge, a bracket on the plate, a rigid arm on the bracket extending parallel with the slot, an operating lever pivoted to the outer 45 end of the arm, a knife blade holder extending parallel with the slot in the frame pivotally connected adjacent to one end to the underside of the lever, a bell crank lever on

the arm having upwardly and downwardly 45 projecting arms extending toward the operating lever, a link connecting the lower arm of the bell crank lever to the operating lever at a point intermediate of the pivotal 50 mounting of the arm and its connection with the blade holder, a link connecting the other arm of the bell crank lever to the blade holder adjacent to the end thereof and opposite its connection with the operating 55 lever, and curved guiding ears on the ends of the blade holder in slidably engagement with the guide slots to guide the blade holder vertically.

3. In a shearing machine, the combination 60 of a plate having a slot providing a cutting edge, a bracket on the plate, a rigid arm on the bracket extending parallel with the slot and having a longitudinal slot formed intermediate of its ends, an operating lever pivoted to the outer end of the arm, a knife 65 blade holder extending parallel with the slot in the frame pivotally connected adjacent to one end to the underside of the lever, a bell crank lever on the arm arranged within the slot therein having upwardly and downwardly 70 projecting arms extending toward the operating lever, a link connecting the lower arm of the bell crank lever to the operating lever at a point intermediate of the pivotal 75 mounting of the arm and its connection with the blade holder, and a link connecting the other arm of the bell crank lever to the blade holder adjacent to the end thereof and opposite its connection with the operating lever.

In witness that we claim the foregoing we have hereunto subscribed our names this 28th day of June, 1913.

JOSEPH VERTUNNI.
ABRAHAM T. ORELLI.
